UNITED STATES PATENT OFFICE.

SAMUEL SLISHMAN, OF CHELSEA, MASSACHUSETTS.

GASOLENE-TANK.

1,382,863.

Specification of Letters Patent. Patented June 28, 1921.

Application filed February 26, 1920. Serial No. 361,383.

To all whom it may concern:

Be it known that I, SAMUEL SLISHMAN, a citizen of the United States, residing at Chelsea, county of Suffolk, Commonwealth of Massachusetts, have invented certain new and useful Improvements in Gasolene-Tanks, of which the following is a specification.

This invention relates to gasolene tanks for automobiles and the like, and particularly to an auxiliary or reserve tank adapted to contain a supply of fuel which may be drawn upon when the supply of the main tank has been exhausted.

My invention is designed to avoid the annoyance of a failure of fuel supply at an inopportune time, and to this end the reserve tank is so related to the main supply tank that the contents of the reserve tank may be emptied into the main tank by the simple manipulation of a valve accessibly positioned within the reach of the driver whenever the supply in the main tank has become exhausted, and whereby moreover the reserve tank when emptied may be conveniently refilled by and during the act of refilling the main tank. By this construction the driver is assured at all times of a reasonable emergency supply of fuel, should the main supply tank be emptied, and his dependency upon the usual fuel gage, which frequently fails to satisfactorily indicate the normal fuel supply, is thereby lessened.

The construction and operation of my device, together with a preferred embodiment illustrative of the principles involved, is described and shown in the accompanying specification and drawings, throughout which like reference characters are correspondingly employed, and in the drawings:

Figure I is a vertical section through a fuel supply tank equipped with my reserve tank and showing the control valve closed to prevent delivery of the contents of the reserve tank.

Fig. II an enlarged detail showing the valve open to permit such delivery, and

Fig. III is a partial plan illustrating in full and dotted lines the open and closed positions of the valve manipulating handle.

I have indicated at 1 the main fuel tank of an automobile or other motor propelled vehicle. The tank 1 is of conventional type and is adapted to contain within itself my improved reserve tank 2 which may be readily applied to the main tank without sub-

stantial modification or reorganization of structure. The filling opening for the tank 1 is indicated at 3 and the feed pipe for delivering the fuel to the carburetor is indicated at A.

My reserve tank is snugly fitted within a compartment 5 formed by vertical partitions 6 fixed in spaced relation within the tank 1 and has preferably the approximately elbow shape illustrated in Fig. I. The several compartments formed by said partitions are in constant communication with each other as by the ports 6¹ in said partitions, and the relation of the reserve tank 2 to the main tank 1 is such that the reserve tank when empty will be filled by and in the operation of filling the main tank.

The delivery of fuel content of the reserve tank 2 into the main tank 1 and thence through the feed pipe A to the carburetor is controlled by a manually operable valve 7 having a seat 8 in the lower end of a tubular guide or shell 9 fixed vertically within the tank 2. The valve 7 may be of conical form and the seat 8 may be of correspondingly shaped form and may have at its bottom an outlet opening 10 delivering into the main tank 1 and controlled by the valve 7, which also simultaneously controls one or more inlet ports 11 opening into said guide from the reserve tank 2 at substantially the level of the bottom wall of said tank.

The stem 12 of the valve 7 may be shouldered as indicated at 13, and a coil spring 14 may be confined between said shoulder and a screw cap 15 threaded onto a nipple 16 surmounting the guide 9 and normally effective to maintain the valve 7 in the closed position shown in Fig. I, wherein the valve prevents ingress of the fuel with the guide 9 from the reserve tank 2 and egress from said guide through the port 10 into the main tank 1.

Beyond the cap 15 the stem 12 may be extended and bent over as an operating handle or crank 17 which may be carried to a conveniently accessible point adjacent the driver's seat for manipulation by the driver to open and close the valve. Said crank 17 is adapted to swing over a cam surface 18 in the opening movement of the valve whereby to raise the valve 7 from its seat 8 and when the valve is fully open to lodge in a locking recess 19 formed in said cam

surface at the upper end of the incline (see Fig. II).

When it is desired to draw upon the reserve tank, the driver swings the valve handle 17 through a part circle to raise the valve 7 to the position shown in Fig. II, wherein the ports 11 are uncovered and the port 10 is opened to the main tank 1 so that the contents of the tank 2 may pass into the 10 tank 1 and thence through the feed pipe A to the carburetor of the engine.

For convenience of filling the tank 2 while the main tank 1 is being filled through the filling opening 3, one or more filling openings 15 are formed in the tank 2 at any desired level therein. These openings may be provided with relatively short pipe sections 20 to prevent the admitted fuel from splashing out in the motion of the car, and near the 20 top of the reserve tank air inlet openings 21 may be provided to assist the automatic filling action. During the filling, the valve 7 may be opened, if desired, to expedite the operation.

25 The location and relation of the ports 10 and 11 is such that both are simultaneously closed or opened by the movement of the valve 7 toward and from its seat 8. The valve itself may be readily removed for 30 cleaning or other purpose by unscrewing the cap 15 while the cam surface 18 and automatic locking engagement of the valve handle 17 in the notch 19 insures not only a full and positive opening of the valve upon operation of the valve handle 17, but relieves the driver of the necessity of any further attention to the interchange of fuel from reserve tank 2 to main tank 1.

Various modifications in the form and 40 construction of my device may obviously be resorted to, all without departing from the spirit of my invention if within the limits of the appended claims.

What I therefore claim and desire to secure by Letters Patent is:

1. In a liquid fuel tank, a main tank, an auxiliary tank having an intake in communication with said main tank whereby filling the main tank fills the auxiliary tank, 50 a tubular valve seat extension fixed within said auxiliary tank and having a valve seat, and an outlet and an inlet port opening into said main and auxiliary tanks, respectively, and a valve stem adjustably mounted in said extension and having a valve coöperative with said seat to simultaneously control said inlet and outlet ports, and means for manipulating said valve stem to move said valve toward and from said 60 seat.

2. In a liquid fuel tank, a main tank, an auxiliary tank inclosed therein and communicating therewith, a valve seat having a tubular extension fixed within said auxiliary tank and having an outlet and an inlet port

opening into said main and auxiliary tanks, respectively, a valve stem slidably and rotatably mounted in said extension and having a valve coöperative with said seat to simultaneously control said inlet and outlet ports, means yieldably maintaining said valve closed, and a manually operable connection for adjusting said valve stem.

3. In a liquid fuel tank, a main tank, an auxiliary tank communicating therewith, a valve seat having a tubular extension fixed within said auxiliary tank and having an outlet and an inlet port opening into said main and auxiliary tanks, respectively, a valve stem slidably and rotatably mounted 75 in said extension and having a valve coöperative with said seat to simultaneously control said inlet and outlet ports, means yieldably maintaining said valve closed, a manually operable connection for rotating said 80 valve stem, and a cam surface for raising said stem as it is rotated to open the valve.

4. In a liquid fuel tank, a main tank, an auxiliary tank communicating therewith, a valve seat having a tubular extension fixed 90 within said auxiliary tank and having an outlet and an inlet port opening into said main and auxiliary tanks, respectively, a valve stem slidably and rotatably mounted in said extension and having a valve coöperative with said seat to simultaneously control said inlet and outlet ports, means yieldably maintaining said valve closed, a manually operable connection for rotating said 95 valve stem, and a cam surface for raising said stem as it is rotated to open the valve, and having a locking notch near the limit of upward movement of the stem to lock the stem in raised position.

5. In a liquid fuel tank, a main tank, an auxiliary tank communicating therewith and having a controllable outlet into the main tank, a valve stem having a valve controlling said outlet, a spring normally maintaining said valve closed, means whereby said valve 105 stem may be rotated, and a cam surface for raising said valve stem as it is rotated to open the valve and having a locking notch at the upper end of its incline whereby to lock the valve stem in raised position.

6. In a liquid fuel tank, a main tank, a reserve tank communicating therewith, a valve seat having a tubular extension and having outlet and inlet ports opening into said main and reserve tanks, respectively, 110 and a valve adjustable relative to said seat for simultaneously controlling both of said ports.

7. In a liquid fuel tank, a main tank, a reserve tank communicating therewith, a 115 valve seat having a tubular extension and having outlet and inlet ports opening into said main and reserve tanks, respectively, and a valve adjustable relative to said seat for simultaneously controlling both of said 120 ports.

ports, a stem carrying said valve and rotatable in said extension, and a cam surface coöperative with said stem to raise said valve from its seat as said stem is rotated to open 5 the valve.

8. In a liquid fuel tank, a main tank, a reserve tank communicating therewith, a valve seat having a tubular extension and having outlet and inlet ports opening into said main 10 and reserve tanks, respectively, and a valve adjustable relative to said seat for simultaneously controlling both of said ports, a stem carrying said valve and rotatable in said extension, and a cam surface coöperative 15 with said stem to raise said valve from its seat as said stem is rotated to open the valve, and means for positively locking said valve in open position.

9. In combination, a main tank, a reserve 20 tank having a port communicating with said main tank and having a discharge port, a valve stem having a valve controlling both of said ports, and a cam surface effective to raise said stem and open said valve.

25 10. In combination, a main tank, a reserve tank communicating therewith and having a discharge opening, a stem, a valve on said stem controlling said opening, a spring effectively disposed to seat said valve and a 30 cam surface operatively disposed in relation

to said stem to maintain said valve raised against the action of said spring.

11. In combination, a delivery line, a main tank and a reserve tank communicating with each other and adapted to discharge into 35 said delivery line, a stem, a valve on said stem controlling communication between said tanks, a spring effectively disposed to seat said valve, and a cam surface operatively disposed relative to said stem to maintain 40 said valve raised against the action of said spring.

12. In combination, a delivery line, a main tank and a reserve tank adapted to discharge into said delivery line, a valve stem, 45 a valve on said stem controlling discharge from said reserve tank, a spring operatively disposed to seat said valve the upper end of said stem having an angular portion, and a stop disposed adjacent to said stem and 50 engageable by said angular portion to maintain said valve raised against the action of said spring.

In testimony whereof I affix my signature in presence of two witnesses.

SAMUEL SLISHMAN.
